Primary Examiner — Rashida C. Walshon(74) *Attorney, Agent, or Firm* — Kilpatrick Townsend & Stockton LLP(57) **CLAIM**

The ornamental design for lace tightening device dial, as shown and described.

DESCRIPTION

1. Lace tightening device dial

1.1 : Top

1.2 : Bottom

1.3 : Back

1.4 : Front

1.5 : Left

1.6 : Right

1.7 : Perspective

The dial can be rotated by a user to tension a lace or tension member via the lace tightening device; the lace tightening device can be attached to an article, such as an article of footwear, in order to tighten the article via the tensioned lace or tension member; the portions illustrated by solid lines are the portions for which the claimed design is intended; the broken lines in drawings represent environment that form no part.

1 Claim, 7 Drawing Sheets(56)
